UNITED STATES PATENT OFFICE.

JENNIE M. CLARK, OF MANCHESTER, NEW HAMPSHIRE.

GARMENT-PROTECTOR.

SPECIFICATION forming part of Letters Patent No. 271,037, dated January 23, 1883.

Application filed July 12, 1882. (No model.)

To all whom it may concern:

Be it known that I, JENNIE M. CLARK, a citizen of the United States, residing at Manchester, in the county of Hillsborough and 5 State of New Hampshire, have invented certain new and useful Improvements in Garment-Protectors, of which the following is a specification, reference being had to the accompanying drawings, and to the letters of 10 reference marked thereon, in which—

Figure 1 represents a side view of my improved garment-protector, which is intended to be applied to the shoulder and arm of the wearer, between the under and outer dress; 15 and Fig. 2 is a plan or front view of the attached shield, which is applied to the body beneath the arm.

Like letters designate like parts in the several views.

20 My invention relates to that class of garment-protectors that are especially designed for ladies' wear, and which are intended to be worn between the under and outer dress at the shoulder, for the purpose of preventing injury to the outer dress from the moisture of perspiration.

In carrying my invention into effect I provide a sleeve, *a*, to the upper end of which is connected a shield, *b*, adapted to fit the body 25 under the arm of the wearer. At the lower end of the sleeve, which may be of any length, is a gathering, band, or cuff, *c*, which is preferably provided with an elastic cord or strip, by which the lower end of the sleeve is se-

cured to the arm, the upper end, which conforms to the shoulder, being secured to the under-clothing by means of pins or stitching, or a button or hook, or any suitable fastening.

The various parts of the protector may be 40 made of any suitable material, the sleeve *a* and shield *b* being preferably composed of some water-proof fabric; or they may be made of any ordinary material and be lined with oiled silk or the like.

It will be observed that a garment-protector formed as described may be readily attached to the clothing, and may be as readily detached when the dress is changed, the same 45 pair of protectors serving for use with several changes of dress. The article is simple, durable, and effective, may be readily washed, and when in use is not likely to become detached or displaced, though no cumbrous fastenings are employed.

Having thus described my invention, what I claim as new, and desire to secure by Letters Patent, is—

A garment-protector consisting of a sleeve, *a*, having a band, *c*, at its end, the sleeve being adapted to inclose the arm and to be attached to the under clothing, and a shield, *b*, constructed to fit the body beneath the arm, substantially as described.

JENNIE M. CLARK.
